METHOD OF AND MACHINE FOR
APPLYING TAPE

Paul H. Dixon, Wenham, Mass., assignor to United
Shoe Machinery Corporation, Borough of Flem-
ington, N. J., a corporation of New Jersey

Application February 9, 1939, Serial No. 255,470

49 Claims. (Cl. 12—51)

This invention relates to methods of taping and taping machines and is herein illustrated with reference to the reinforcement of shoes or parts thereof by the use of tape.

5 Shoe parts are commonly reinforced by the use of adhesive tape which is progressively applied to the shoe part by a pressing member which is arranged to press the tape and work together and to advance the tape and work by small in-

10 crements and hence at a relatively low speed. Moreover, the tape is commonly applied to the shoe part while the latter is in a flat or other-than-normal shape with the result that when the shoe part is embodied in a shoe—the tape usually 15 being applied to a normally concave surface of the shoe part—the forming of the shoe part into its normal shape causes the tape to pucker with a corresponding loss in its value as a reinforcement.

20 Prior machines of this type are also commonly provided with mechanism for pulling the tape from a source of supply so that the force which is required to pull off the tape will not hamper the feed movement of the work and tape. Such 25 delivery of the tape, however, to the point where it is applied to the work under substantially no tension, aggravates the difficulty referred to above because the tape does not become effective 30 as a reinforcement for the shoe part to which it is attached until the shoe part has been stretched to take up the initial resiliency of the tape.

In view of the foregoing, it is a general object of the invention to provide an improved method of and a machine for uniting a tape and shoe part more rapidly than is possible by the use of 35 a progressively operated machine and in such a way that the reinforcing tape is effectual to resist any stretching of the shoe part.

Accordingly, the invention in one aspect provides, an improved method of taping which consists in tensioning a length of tape sufficient for a complete taping operation to remove its inherent elasticity and, while holding the tape under tension, pressing a work piece and the entire length of tape together simultaneously to unite the tape and work piece. By practicing this method substantially less time is required in the application of the entire length of tape than 45 is consumed in applying the tape progressively; and because the work is united with the entire length of tape while it is under tension, any tendency of the tape to pucker on the work piece is minimized.

50 Further to insure against this tendency, the

invention also contemplates a method including as steps in addition to those of the method stated above that of forming the tape into the shape it is to have in a finished shoe, that is, a concavo-convex formation, and then while holding the formed tape under tension forming the work piece into the same shape and finally uniting the work piece and the tape.

5 In another aspect the invention provides, as one feature, a taping machine comprising means 10 for clamping a tape against a work support, the clamp and work support then being movable to cause a length of tape sufficient for a complete taping operation to be wrapped about the support under substantial tension and pressing means 15 cooperating with the support to unite a work piece with the entire length of tape on the support simultaneously.

20 Preferably, and as herein illustrated, the shape of the pressing means and the work support about which the tape is wrapped is substantially like that of the shoe part to be reinforced when embodied in a finished shoe. Accordingly, any 25 tendency of the tape to pucker with the disadvantages noted above is avoided because the tape and work piece are united while in their normal state of curvature and while the tape is under tension.

25 To insure against the possibility that the tension required to pull the tape from the source of supply may not be adequate to remove its initial resiliency as it is wrapped about the support, the 30 illustrated machine includes means constituting another feature of the invention arranged to set up such tension in the tape, in addition to that 35 which is caused by pulling it from its source of supply, as is necessary to bring it to a substantially non-stretching condition when it is wrapped about the support.

40 In accordance with another feature of the invention, the illustrated work support is provided with opposed work engaging surfaces adapted to be brought successively into operative relation with respect to the presser member when the work support is rotated, the tape to be applied in a succeeding operation being wrapped about one of these surfaces as the other is moved to its inoperative position.

45 Invention is also to be recognized in the tape 50 clamping means referred to above which comprises clamps associated with each of the work engaging surfaces of the support and means for operating the clamps so that the tape is held clamped under tension throughout the tape ap- 55

plying operation against that work engaging surface of the support which is in operative position, one clamp being retracted from and then advanced toward the support during each rotative movement of the latter thereby to grip a succeeding length of tape against the support preparatory to its being pulled from the source of supply.

To facilitate the cutting of the length of tape on the support from the succeeding tape, each clamp is constructed in accordance with another feature of the invention so as to clamp the tape against the support at spaced points between which the tape is to be cut. Thus, the tape spanning the points where it is clamped is held taut during the cutting operation and both ends of the tape adjacent to the cut are held against the support.

The invention also provides an improved mounting for a pressing member adapted to press a work piece against a support which permits unobstructed movement of work pieces onto the work support and their removal therefrom. To this end, the invention provides means for moving the pressing member from an inoperative position normally above and behind the support, first forwardly, and then heightwise of the support into engagement with the work piece thereon, the movement of the pressing member forwardly of the support being arrested when the pressing member is directly above the support.

These and other features of the invention will appear more fully from the following detailed description when read in connection with the accompanying drawings and will be pointed out in the appended claims.

In the drawings,

Fig. 1 is a side elevation of an illustrative machine embodying the invention, a portion of the frame having been broken away to expose the operating mechanism;

Fig. 2 is a plan view of the machine illustrated in Fig. 1, parts of the operating mechanism for the pressing member being omitted;

Fig. 3 is an enlarged front elevation of the rotatable work support and the mechanism cooperating therewith to clamp and sever the tape;

Fig. 4 is a front elevation of the machine shown in Fig. 1;

Fig. 5 is a view in perspective of a shoe quarter having a back seam across which a reinforcing tape has been applied in accordance with the invention, and

Figs. 6 and 7 are fragmentary side elevations of the operating mechanism for the pressing member at successive positions in its movement toward its operative position.

The illustrated machine comprises a form 10 adapted to be engaged by the ridge of the back seam S of a quarter Q (Fig. 5), guides 12 (Figs. 1 and 4) disposed at opposite sides of the form and adapted to engage the sides of the ridge and portions of the quarter adjacent thereto, and a rotatable support or member 14 (Fig. 3) adapted to be engaged by a marginal portion of the quarter at each side of the seam ridge adjacent to its top edge, the form, guides and support also being so shaped as to support the quarter in substantially its normal curvature both longitudinally and transversely of the seam ridge. When the support or member 14 is rotated a length of tape T, sufficient for a complete taping operation, is drawn from a source of supply under sufficient tension to remove its inherent elasticity,

wrapped about and is clamped against the support 14 at both ends, and is cut from the trailing length of tape by a combined tape clamping and cutting device 16. A work piece to be reinforced having been placed against a stop 15 attached to the support 14, over the tape on the support 14, and over the guides 12, the seam ridge being disposed between the guides, a pressing member 18 is moved into engagement with the entire length of the back seam area of the work piece simultaneously and causes the quarter and tape to be united and the quarter to be shaped into its desired form. The pressing member is then raised to permit the removal of the taped quarter from the form, the attached length of tape having been cut from the trailing supply strip. The rotatable support is then turned through 180° to draw off another length of tape and to present it into position to be applied to the next work piece to be taped.

Referring more specifically to the means in the illustrated machine for positioning and supporting of the quarter Q, the form 10 is secured to the front of the frame 20 by a screw 22 (Fig. 1). The quarter is placed over the pair of guides 12 the upper portions of which closely embrace the sides of the form 10 and are spaced sufficiently to receive the seam ridge therebetween. Thus, when the quarter is pulled downwardly by the operator against the guides 12, the latter engage the sides of the seam ridge and straighten it longitudinally and also form the quarter transversely of the seam. In response to the downward pressure of the quarter against the guides the guides 12 yield downwardly being mounted to slide vertically between plates 24 integral with the form 10, the plates 24 carrying screws 26 (Fig. 4) which extend through vertically elongated slots 27 in the guides 12. The guides are normally held in their uppermost positions and separated from each other at their upper ends by a spring 28 which connects the lower ends of the guides 12, the latter being adapted to bear against a cam member 30 which is fixed to the form 10 by means of screws 32. The cam surfaces of the member 30 are so shaped as to cause the top edges of the guides 12 to approach each other at the same rate as they are lowered so as eventually to grip the sides of the portion of the seam ridge which extends beyond the line of stitching when the edge face of the seam ridge is in engagement with the form 10 thereby insuring the alignment of the seam ridge with the middle of the form.

The support 14 is provided with opposed tape supporting surfaces the shape of which corresponds to that of the upper surfaces of the guides 12 when in their operative position and is fixed to a shaft 34 (Fig. 1) one end of which is rotatably mounted at 36 in the frame 20 adjacent to the form 10. Near its opposite end, the shaft 34 is rotatably mounted in the outer end of a lug 38 extending toward the center of the machine from the left-hand side of the frame 20 (Fig. 2). The opposed tape supporting surfaces of the support 14 are adapted to be brought successively into their operative position (in which the upper surfaces of the support and guides 12 are continuous with each other) by intermittent rotative movements of the shaft 34 through one-half of a revolution. Thus, during each half revolution of the support 14, it pulls off a length of tape sufficient for a complete taping operation and this tape is clamped against the work support while under tension and is cut from the trailing length of tape as will now be described in detail.

The combined tape clamping and cutting device 16 includes duplicate instrumentalities, one being disposed at each side of the support 14, each comprising an arm 40 having an elongated slot 42 which permits the arm 40 to slide axially of the support 14 and with respect to a block 44 which, by means of a screw 46, is pivoted to a collar 48 fixed to the shaft 34. Each arm 40 carries at its forward end a knife 50 (Fig. 3) which, when the arm 40 is swung toward the support 14, cooperates with another knife 52 mounted at one side of a recess 54 in the support to sever the tape T. The knife 52 is adjustably fixed to the rear side of the support 14 by a screw 53 which passes through a slot in the shank of the knife so as to permit the knife edge, upon being sharpened, to be set flush with the work engaging surface of the support 14. In order to insure that the tension in the tape T will not be relieved either before or after it is cut, the illustrated machine is provided with means presently to be described for clamping each end of the tape against the support throughout each taping operation. This means comprises clamping members 56 and 58 associated with each of the arms 40 both of which cooperate with the support 14 to clamp the tape thereagainst before the cutting edges of the knives 50 and 52 pass each other. The member 56 is fixed to the arm 40 and is adapted to enter the recess 54 just ahead of the knife 50 and cooperate with a shoulder 60 at the side of the recess opposite to the knife 52 to clamp against the support 14 the leading end of the trailing portion of the tape before and after it is cut. Similarly, the member 58 is pivoted to the arm 40 at 62 and is normally held in a position overlying the cutting edge of the knife 50 by a spring 64. Thus, when the cutting and clamping device 16 is moved toward the support 14 the member 58 also clamps the trailing end of the length of tape T against the support 14 before it is severed, the member 58 being permitted to yield by the spring 64 so as not to inhibit the movement of the arm 40 which is necessary to cause the knife 50 to sever the tape.

The tape is tensioned and is directed in alignment with the support 14 by being led between rolls 66, 68 rotatably mounted on the frame 20 below the support 14, adjustable friction means of any suitable type being associated with the roll 68 so as to set up sufficient tension in the tape which is wound about the support 14 to remove substantially all of its inherent elasticity.

The operation of the combined tape clamping and cutting devices 16 will now be traced through 360° of their movement from their positions as illustrated in Fig. 3. A work piece having been pressed against the length of the tape T in Fig. 3, the support 14 (and the devices 16) are swung through 180°. At the beginning of this movement, the forward end of the left-hand arm 40 is swung away from the support 14 to unclamp the leading end of the tape T permitting the work piece with the tape attached thereto to be removed from the machine against the yielding, clamping action of the right-hand clamping member 58. The right-hand clamping device 16 is maintained in its operative relation with respect to the support 14 throughout this rotative movement thereby causing the leading end of a fresh length of tape to be securely held between the support 14 and the clamping member 58 whereby a new length of tape T, sufficient for a succeeding taping operation, is drawn under ten-

sion from the source of supply and is wrapped about the formerly lower surface of the support 14. During the corresponding movement of the left-hand clamping and cutting device 16 toward the right-hand side of the machine, after being retracted from the work support radially as stated above, it is then moved axially of the support rearwardly of the machine so as to avoid any interference with the rolls 66, 68 or with the tape at the lower side of the support. Subsequently, and just before the completion of the 180° rotative movement of this device 16 into its right-hand position, it is advanced axially of the support 14 so that it overlies the tape and then is moved radially of the support again to clamp and sever the tape as indicated by the position of the right-hand clamping device 14 in Fig. 3. Thus, during the continued operation of the machine both ends of the tape T are clamped throughout the applying operation insuring that the tape will be applied to the work while under tension and while it conforms to the normal transverse curvature of the work piece. This operation of the clamping devices 14 is effected by the mechanism now to be described.

This mechanism comprises a cam 69 (Fig. 2) which is fixed to the lug 38 and has a groove 70 the bottom surface of which effects the movement of the arms 40 radially of the support 14 and the sides of which move the arms 40 axially of the support in the manner described above. The groove 70 is arranged to receive the heads of screws 72 which are threaded in the rear ends of the arms 40 and may be locked in adjusted position thereon by means of nuts 74. The screws 72 are held seated in the groove 70 by springs 76 which connect the arms 40 with a pin 78 fixed to the shaft 34.

The above described operation of the clamping and cutting devices 16 results from their being rotated bodily with respect to the cam 69 by operator controlled mechanism comprising a bevel pinion 80 rotatably mounted on the shaft 34 and adapted to be driven by a segmental gear 82 which is mounted to swing freely on a shaft 84 journaled in the frame 20. The shaft 84 carries at its right-hand end a pulley 86 adapted to be driven by a belt from any suitable source of power. The gear 82 is operated by a link 88 which is connected at its lower end to a treadle 90 (Fig. 1) which is normally urged upwardly by a spring 92 connecting the treadle with the bottom of the frame 20. Thus, when the treadle 90 is lowered the pinion 80 is rotated in a counterclockwise direction (Fig. 4) and through the connections, now to be described, causes the support 14 with its associated clamping and cutting devices 16 to be rotated through 180° for each actuation of the treadle 90. These connections comprise a pawl 94 (Fig. 1) mounted in the pinion 80 to slide axially thereof and which is urged into yielding engagement with a double-toothed ratchet 96 by a spring 98, the ratchet being fixed on the rearmost end of the shaft 34. Each rotative movement of the shaft 34 is stopped at such a point that one of the tape supporting surfaces of the support 14 is in its operative position by means comprising a collar 100 fixed to the shaft 34 and bored to receive a spring pressed ball 102 which cooperates with either of two recesses 104 formed in the cam 69.

Assuming now that a length of tape T has been drawn from the source of supply and is brought to its position as illustrated in Fig. 3, a shoe quarter to which the tape is to be ap-

plied across its back seam, as indicated in Fig. 5, is placed over the form 10 and is lowered thereagainst by the operator as explained above. The operator then actuates mechanism now to be described which causes the pressing member 18 to be moved toward the form to press the quarter against the tape and to flatten the seam ridge and shape the quarter in the vicinity of the seam ridge about the guides 12 and the support 14. The pressing member 18 is carried by a bent lever 106 having a cylindrically shaped end 108 which is seated in a complementary recess in the pressing member 18. To facilitate the placing of work pieces on the form 10 the lever 106, between successive pressing operations, is swung rearwardly of and above the form on a link 110 which is pivotally connected to the frame 20 at 112, and to the lever 106 by a pin 114. The lever 106 is operated by a toggle comprising links 116, 118 which are pivoted to each other at 120, the link 116 being pivoted to the lever 106 at 122. The link 118 is mounted to slide in an arm 124 and a bushing 126 threaded in another arm 128, the arms being formed integrally with a lever 130, the hub of which is arranged to pivot freely on the shaft 84. A spring 132 at one end abuts the bushing 126 and at the other end a shoulder 134 on the link 118, thereby tending normally to urge the link 118 upwardly with respect to the lever 130, this movement being limited by check nuts 136 adapted to engage the lower edge of the bushing 126. To adjust the pressure of the pressing member 18 against the work piece, as will be described later, the bushing 126, which is threaded in the arm 128, may be turned in or out of the arm so as to vary the stress in the spring 132.

To begin the pressing operation, the lever 130 is swung downwardly (Fig. 6) by the operator by lowering a treadle 138 to which is pivoted a link 140, the latter being connected at 142 to the lever 130. The lever 130 is thus lowered to such an extent that a cam roll 144 rotatably mounted on the end of the lever 130 is moved through a peripheral opening of a cam track 146 in a cam 148 mounted to rotate freely on a shaft 150 which is rotatably mounted in bearings in the sides of the frame 20. During this movement of the lever 130, the operating mechanism for the pressing member 18 is moved first from its position as illustrated in Fig. 6 to the position indicated in Fig. 7, the link 110 having been swung forwardly until the pressing member 18 is directly over the form 10, this movement of the link 110 being limited by a set screw 152 which is threaded in the upper end of the link 110 and is adapted to bear against the frame 18. During this movement no relative rotation occurs between the toggle links 116 and 118 such rotation being prevented by a spring 154 fastened at one end to the pivot 122 and at its other end to a pin 156 carried by the link 116. The spring 154 thus tends to hold an adjustable set screw 158 threaded in the link 116 against an extension 160 of the link 118. However, further movement of the lever 130 beyond the point where the screw 152 engages the frame 20, causes the toggle links 116, 118 to be straightened and the link 118 to yield against the pressure of the spring 132 thereby setting up a yielding pressure of the pressing member 18 against the work piece on the guides 12 and support 14. Toward the end of the movement of the lever 130 into the cam track 146, operating mechanism for the cam 148, presently to be described, is tripped and causes

the cam 148 to be power operated through a complete revolution during which the cam, because of the eccentric shape of the track 146, causes the presser member 18 to be held down with an increased pressure against the work. 5 This operating mechanism comprises the shafts 84 and 150, referred to above, which are continuously rotated, the shaft 150 being connected to the shaft 84 by means of an intermediate shaft 162 which is journaled in bearings in the left-hand side wall of the frame 18 and carries at its rear end a bevel gear 164 meshing with another bevel gear 166 fixed to the shaft 84. The shaft 162, near its forward end, carries a worm 168 which meshes with a gear 169 fixed to the shaft 150. Splined on the shaft 150 for axial movement with respect thereto is a sleeve 170 the left-hand end of which is grooved at 172 to receive the forked arm 174 (Fig. 4) of a bell crank 176 which is pivoted at 178 to the base of the 10 frame 20, the other arm 180 of the bell crank being disposed in the path of a member 182 fixed to the treadle rod 140. As the lever 130 is moved to bring the roll 144 into alignment with the cam track 146, the member 182 strikes a detent 184 15 having a tooth 186 which normally abuts a shoulder 187 (Fig. 6) in the periphery of the cam 148. The detent 184 is arranged to slide vertically in a bore 188 formed in a lug 190 extending upwardly from the base of the frame 20 and is normally held in engagement with the cam 148 by a spring 192. Simultaneously with the downward movement of the detent 184 out of engagement with the cam 148, the sleeve 170 is moved to the right (Figs. 2 and 4) with respect to the shaft 150 by the arm 174 to cause a clutch face 194 on the sleeve 170 to engage a complementary clutch element 196, which is fixed to the cam 148 by means of screws 198, thereby establishing a driving connection between the shaft 150 and the cam 148. 20 Immediately after the beginning of the rotation of the cam 148, the roll 144 on the lever 130 is received in the cam track 146 thereby relieving the operator of the necessity of holding the treadle 138 down. However, toward the end 25 of a complete revolution of the cam 148, when its peripheral opening is above the roll 144, the lever 130 is permitted to rise suddenly under the influence of a spring 200 (Fig. 1) which connects the treadle 138 with the bottom of the 30 frame 20. Thus, as the lever 130 is again raised toward its uppermost position the clutch element 194 is separated from the clutch element 196 thereby interrupting the drive of the cam 148 the rotation of which is stopped in a predetermined position as illustrated in Fig. 6 by the engagement of the tooth 186 of the detent 184 with the shoulder 187 on the cam 148. Moreover, as the lever 130 thus suddenly rises, the toggle 116, 118 is broken, the link 110 is swung 35 rearwardly, and the pressing member 16 is lifted above the form 10 and moved rearwardly thereof to facilitate the removal of the taped work piece from the support 14.

The operation of the illustrated machine and 40 its use in carrying out the method aspect of the invention will now be summarized. Assuming that the friction means associated with the roll 68 is so adjusted as to set up sufficient resistance in the tape to remove its inherent elasticity, the support 14 is rotated when the treadle 90 is tripped by the operator to draw a length of tape T sufficient for a complete taping operation from the source of supply, this length of tape being gripped at its leading end between 45 75

the support and the clamping member 56. As described above, toward the end of each 180° movement of the support 14 the combined clamping and cutting device 16, then at the right-hand side of the machine (Fig. 3), is actuated by the rotative movement of the arm 40 relatively to the cam 69 to cause the trailing end of the tape to be similarly clamped against the support by the clamping member 58 whereby the 10 length of tape T, while wrapped about the support, is maintained under the same state of tension as when it was drawn between the rolls 66 and 68. At the same time the leading end of the succeeding length of tape is also clamped 15 against the support 14 by the clamping member 56 and just before the support comes to rest, the knife 50 passes the knife 52 thereby severing the tape between the sections thereof clamped against the support by the members 56 and 58.

20 While the tape T is thus held under tension on the support 14, the operator places a shoe quarter or other work piece to be reinforced over the guides 12 with the seam ridge of the work piece, if it is a shoe quarter, extending 25 downwardly between the upper edges of the guides. The quarter while grasped by the operator at each side of the seam is then lowered causing the portions of the quarters contiguous to the seam to assume the shape of the guides 30 12 and bringing the end face of the seam ridge substantially into contact with the form 10. During this movement of the work piece the guides 12, under the control of the cam member 35 30, gradually approach each other so that their upper edges engaging the sides of the seam ridge restrain the latter against lateral displacement, straighten it and aline it with the longitudinal center line of the form 10.

The operator then depresses the treadle 138 40 which first causes the pressing member 18 to be held with a light yielding pressure against the work piece. Further downward movement of the treadle causes the inter-engagement of the clutch elements 194 and 196 which then drive 45 the cam 148 through a complete revolution which, through the above described operating mechanism for the pressing member 18, causes the latter to exert a gradually increasing and then diminishing pressure on the work piece 50 throughout one revolution of the cam 148 without the help of the operator. As the work supporting surfaces of the guides 12 and support 14 are shaped in conformity to the shape which the shoe quarter is to have in a finished shoe 55 and since the work engaging surfaces of the pressing member 18 and support 14 are coextensive with the area of the work to which the tape is to be attached, the work piece is shaped and united with the entire length of tape simultaneously while in its normal state of curvature. Thus, any puckering of the tape in the finished 60 shoe is avoided.

As the cam 148 approaches the end of each revolution, its peripheral opening permits the lever 130, and hence the pressing member 18, to rise above and rearwardly of the form 10. At the beginning of the succeeding pressing and taping operation, the left-hand clamping and severing device 16 is retracted from the support 14 thereby freeing the leading end of the tape which is attached to the work piece, and permitting the operator to withdraw the work piece from the form.

Having thus described my invention, what I

claim as new and desire to secure by Letters Patent of the United States is:

1. That improvement in methods of taping which consists in tensioning a length of tape sufficient for a complete taping operation substantially to remove its inherent elasticity, and while holding the tape under tension, pressing a work piece against the entire length of tape simultaneously to unite the tape and work piece. 5

2. That improvement in methods of taping which consists in tensioning a length of adhesive tape sufficient for a complete taping operation substantially to remove its inherent elasticity, forming the tape into the shape it is to have in a finished shoe, and while holding the formed tape under tension, pressing a work piece against the entire length of tape simultaneously to unite the tape and work piece. 15

3. That improvement in methods of taping which consists in drawing from a source of supply a length of adhesive tape sufficient for a complete taping operation, tensioning the said length of tape substantially to remove its inherent elasticity, and pressing a work piece against the entire tensioned length of tape simultaneously. 20 25

4. That improvement in methods of taping which consists in drawing from a source of supply a length of adhesive tape sufficient for a complete taping operation under such tension 30 as to remove substantially all of its inherent elasticity, imparting a concavo-convex formation to said tape while under tension, and pressing a work piece against the entire formed and tensioned length of tape simultaneously. 35

5. That improvement in methods of taping which consists in drawing from a source of supply under tension sufficient to remove its inherent elasticity, a length of adhesive tape adequate for a complete taping operation, and while holding the tape under tension, pressing a work piece 40 and the entire length of tape together simultaneously.

6. That improvement in methods of taping which consists in tensioning a length of tape 45 adequate for a complete taping operation sufficiently to remove its inherent elasticity, forming said length of tape while under tension and a work piece into substantially the shape they are to have in a finished shoe, and pressing the work 50 piece and the entire tensioned length of tape together simultaneously.

7. That improvement in methods of taping which consists in tensioning a length of tape sufficient for a complete taping operation substantially to remove its inherent elasticity, and while holding the tape under tension, pressing a work piece against the entire length of tape simultaneously to unite the tape and work piece, 55 and cutting the tape. 60

8. That improvement in methods of taping which consists in shaping a length of tape sufficient for a complete taping operation into the form it is to have in a finished shoe, tensioning the formed tape, and while holding the tape under tension, pressing a work piece against the entire formed length of tape simultaneously, and cutting the tape. 65

9. In a taping machine, means for tensioning a length of tape sufficient for a complete taping operation substantially to remove its inherent elasticity, means for holding said tape under tension, and means for pressing a work piece against the entire length of tape simultaneously 70 to unite the tape and work piece. 75

10. In a taping machine, means for tensioning a length of adhesive tape sufficient for a complete taping operation substantially to remove its inherent elasticity, means for forming the tape into the shape it is to have in a finished shoe, means for holding the formed tape under tension, and means for pressing a work piece against the entire length of tape simultaneously to unite the tape and work piece.
- 10 11. In a taping machine, a work support, a clamp cooperating with said support to grip a tape, said support and clamp being mounted to move as a unit to cause a length of tape to be wrapped about said support, a member cooperating with said support to press a work piece against the tape, and means for alternately moving said member and said support and clamp.
- 15 12. In a taping machine, a work support, a pressing member, means for clamping a tape against the work support, said support and clamp being rotatable as a unit to cause a length of tape sufficient for a complete taping operation to be wound about said support, and means for alternately rotating said support and clamp and moving said pressing member toward said support to press a work piece against said tape and support.
- 20 13. In a taping machine, a work support, pressing means, said support and means being alternately movable relatively to each other to unite an adhesive tape and work piece disposed therebetween, and tape clamping means associated with said support, said support and tape clamping means being mounted to move together to cause a length of tape sufficient for a complete taping operation to be drawn from the source of supply, wrapped about said support and presented to the pressing means.
- 25 14. In a taping machine, a work support, pressing means, said support and means being movable relatively to each other to unite an adhesive tape and work piece disposed therebetween, a clamp constructed and arranged to grip the tape, and means for operating said clamp to cause it successively to grip and release the tape, said support and clamp being mounted to move together while the tape is clamped to cause a length of tape sufficient for a complete taping operation to be drawn from the source of supply and to be wrapped about said support.
- 30 15. In a taping machine, a work support mounted for movement between an operative and inoperative position, a pressing member, a clamp cooperating with said support to hold a tape thereagainst, means for operating said clamp constructed and arranged to cause the clamp to hold the tape against the support as it is moved from its inoperative position to its operative position, means for successively retracting the clamp from and advancing the clamp toward said work support during its movement from its operative position to its inoperative position, and means for moving said pressing member toward said work support after the latter has been moved into its operative position.
- 35 16. In a taping machine, a work support, a clamp cooperating with said support to hold an adhesive tape thereagainst, said support and clamp being mounted to move together to cause a length of tape to be wrapped about said support, means for resisting the feed movement of the tape whereby it is tensioned sufficiently to remove the inherent elasticity from the tape on the support, and pressing means cooperating with
- 40 said support to press the tape and a work piece together whereby they are adhesively united.
- 45 17. In a taping machine, a work support, a pressing member, said support and member being mounted for movement relatively to each other to press together a work piece and tape disposed therebetween, means for clamping the tape against said support, means for moving said support and clamping means between each pressing operation to cause a length of tape sufficient for a complete taping operation to be wrapped about said support, and means for cutting the tape.
- 50 18. In a taping machine, a rotatable work support carrying a clamp adapted to hold the tape against said support, a cutter associated with said clamp, said cutter and clamp being mounted to move together toward and away from said support successively to clamp and cut the tape, a pressing member, and means for alternately moving said pressing member toward and away from said support and rotating said work support.
- 55 19. In a taping machine, a work support having a plurality of work engaging surfaces, means for periodically rotating said support to bring said surfaces successively into operative position, means for clamping said tape against said work support prior to each rotation thereof, means for pressing a work piece against the tape on said support, and means operable after the tape has been clamped against said support to cut the tape.
- 60 20. In a taping machine, a work support, a clamp cooperating with said support to grip a tape disposed therebetween, said clamp and support being movable together to cause a length of tape to be drawn from the source of supply, said clamp being mounted to move with respect to said support toward and away therefrom, and means actuated by the movement of said support and clamp together to move said clamp with respect to said support to grip the tape.
- 65 21. In a taping machine, a work support, a clamp cooperating with said support to grip a tape disposed therebetween, said support and clamp being mounted to rotate together to cause a length of tape to be wrapped about said support, and means actuated by the rotation of said support and clamp for moving said clamp toward and away from said support to grip and release the tape respectively.
- 70 22. In a taping machine, a rotatable work support, a clamp mounted for movement axially and radially of said support to grip a tape disposed therebetween, said support and clamp being mounted to rotate together to cause the tape to be drawn from the source of supply and to be wrapped about said support, and means arranged to utilize the rotative movement of said clamp to move the latter toward and away from said support.
- 75 23. In a taping machine, a work support, a clamp cooperating with said support to grip a tape disposed therebetween, said support and clamp being mounted to move together to cause a length of tape to be drawn from a source of supply, and means actuated by the movement of said support and clamp for moving said clamp toward and away from said support, said means comprising a cam and a spring arranged to hold said clamp against said cam.
- 80 24. In a taping machine, a work support, a tape clamp associated with said support, said support and clamp being mounted to rotate to-

gether to cause a length of tape to be drawn from a source of supply and to be wrapped about said support, and means for operating said tape clamp comprising a cam shaped and arranged successively to cause said clamp to grip the tape and then to release the tape.

25. In a taping machine, a work support mounted to rotate intermittently, a tape clamp mounted for movement axially and radially of said support to grip a tape disposed therebetween, and means for operating said clamp during one rotative movement of said support to clamp the tape, said means being arranged to move said clamp radially and axially with respect to said support simultaneously during a succeeding rotative movement of said support to release the tape.

26. In a taping machine, a rotatable work support, tape clamping means carried by said support, said means comprising a lever mounted to slide and swing on said support, means for operating said lever in response to rotative movement of said support, said means comprising cam surfaces shaped and arranged to move said lever radially and axially with respect to said support simultaneously.

27. In a taping machine, a rotatable work support, a clamping member cooperating with said support to grip a tape disposed therebetween, said clamping member being mounted to slide on a fulcrum about which said member is adapted to swing radially of said support, and means constructed and arranged to utilize the rotative movement of said work support simultaneously to cause said member to slide axially and swing radially with respect to said support.

28. In a taping machine, a work support, a clamp mounted for movement axially and radially of said support to grip the tape, said support and clamp being mounted for movement together to cause a length of tape sufficient for a complete taping operation to be wrapped about said support, and means actuated by the movement of said clamp with said support for moving said clamp simultaneously radially and axially of said support.

29. In a taping machine, a work support, a tape clamp associated with said support, means for intermittently moving said support and clamp together to cause a length of tape to be drawn from a source of supply, and means for operating said clamp during one of its movements with the support to clamp the tape, said means being arranged to utilize a succeeding movement of the support and clamp to cause said clamp to release the tape.

30. In a taping machine, a work support, a tape clamp mounted for movement toward and away from said support to clamp and release a tape disposed therebetween, said support and clamp being mounted for intermittent rotative movement, and means for operating said clamp during one rotative movement of said support to clamp the tape thereagainst, said means being arranged to move said clamp away from said support to release the tape during a succeeding rotative movement of said support.

31. In a taping machine, a work support, a tape clamp cooperating with said support to grip a tape disposed therebetween, said support and clamp being mounted to move together intermittently to cause a length of tape to be drawn from a source of supply, and means arranged to utilize the movement of said support and clamp together to move said clamp with re-

spect to said support, said means comprising a cam shaped and arranged to hold said clamp against the tape against said support during one of its movements and to move said clamp to release the tape during the succeeding movement of said support.

32. In a taping machine, a work support, a tape clamp associated with said support, means for intermittently moving said support and clamp together to cause a length of tape to be drawn from a source of supply, clamp operating means arranged to cause said clamp to hold the tape against said support throughout one of its movements, a second tape clamp, said clamp operating means being arranged to cause said second clamp to be moved successively out of and then into engagement with the tape on said support during the said movement thereof.

33. In a taping machine, a work support, a pair of tape clamps carried by said support, means for intermittently rotating said support and clamps together to cause a length of tape to be drawn from a source of supply, and clamp operating means comprising a cam constructed and arranged to cause one of said clamps to hold the tape against said support during one movement thereof and successively to move the second clamp away from and then toward said work support during the same movement thereof.

34. In a taping machine, a work support, a pair of tape clamps cooperating with said support to hold an adhesive tape thereagainst, said support and clamps being movable together intermittently to draw lengths of tape from a source of supply, clamp operating means arranged to utilize the movement of said support and clamps together to move said clamps toward and away from said support, said means comprising a cam shaped and arranged to cause one of said clamps to hold the tape against said support during one movement thereof and to move the other clamp successively away from and then into engagement with the tape on said support during the same movement thereof.

35. In a taping machine, a work support and a tape clamp associated with said support, said support and clamp being intermittently movable together to cause a length of tape to be wrapped about said support, said clamp being constructed and arranged yieldingly to clamp an end of the tape on said support and positively to clamp an end of the tape to be wound upon the work support during a succeeding movement thereof.

36. In a taping machine, an intermittently movable work support, tape clamping means cooperating with said support when it is moved to draw a length of tape from a source of supply, said means comprising clamping members arranged to clamp the tape at spaced points against said support and a cutter arranged to sever the tape between the clamped portions thereof.

37. In a taping machine, a work support, tape clamping means, said support and tape clamping means being movable together to draw a length of tape from a source of supply, said means comprising a pair of clamping members, operating means for said members arranged to cause one of them to hold the leading end of the tape against said support during one movement thereof, the other clamping member being arranged to grip the trailing end of the tape on said support and the leading end of the succeeding length of tape, the last mentioned clamping member carrying a knife arranged to cut the tape between the portions clamped thereby.

38. In a taping machine, a work support having opposed work engaging surfaces, a pressing member mounted for movement intermittently toward and away from said support, means for 5 rotating said work support between successive movements of said pressing member to cause said surfaces to be moved between operative and inoperative positions, clamping members for holding a length of tape at spaced points against said support, and means operable during each rotation of said support to hold one of said clamping members in operative relation to said support and to cause the other member to be successively retracted from and advanced into operative relation to said support during the same movement thereof.

39. In a taping machine, a work support, a clamp cooperating with said support to grip a tape, said clamp and support being rotatable to 20 wind a length of tape about said support, a second clamp for holding said tape against said support at a point spaced from the first mentioned clamp, a shear associated with said second clamp to cut the tape, and means cooperat- 25 ing with said support to press a work piece against the tape on said support.

40. In a taping machine, a work support having opposed work engaging surfaces, means for rotating said work support to move its said surfaces between operative and inoperative positions, clamps for holding a length of tape at spaced points against said support, means for operating said clamps constructed and arranged to hold one in operative relation to said support 30 and to cause the other clamp to be successively retracted from and advanced into operative relation to said support during its movement between successive positions, means for pressing a work piece against the length of tape between said clamps, and means for cutting the tape.

41. In a taping machine, a rotatable work support, a pair of clamps mounted to rotate with said support, a shear associated with each of said clamps, means for moving each of said clamps alternately out of and into operative relation with respect to said support, a pressing member mounted for movement toward and away from said support, and means for operating said member and one of said shears successively to press a work piece against the tape and cut the tape.

42. In a machine for operating upon a work piece having a seam ridge, a seam ridge support, guides disposed at opposite sides of said support and mounted for movement heightwise and laterally thereof, a member associated with and arranged to utilize their movement heightwise of said support to move them laterally thereof, and a pressing member cooperating with said support to press the seam ridge, said guides and member cooperating with each other to press the portions of the work piece contiguous to the seam ridge.

43. In a machine for operating upon a work piece having a seam ridge, a seam ridge support, guides overlying said support and being spaced to receive a seam ridge therebetween, said guides being mounted for yielding movement toward said support, means arranged to utilize the yield-

ing movement of said guides to cause each of them to be moved toward the other at the same rate whereby the seam ridge is gripped between them and alined with said support, and a pressing member cooperating with said support and guides to press the seam ridge and portions of the work piece contiguous thereto.

44. In a machine for operating upon a work piece having a seam ridge, a seam ridge support, guides mounted to slide toward said support and 10 to swing toward each other, said guides normally being spaced so as to receive a seam ridge therebetween, connections between said guides arranged to utilize their sliding movement toward said support to cause them to be swung toward 15 each other, and a pressing member cooperating with said support to press the seam ridge and co-operating with said guides to press the portions of the work piece contiguous to the ridge.

45. In a machine for use in making shoes, a 20 work support, a pressing member disposed normally above and behind said support, means for moving said pressing member forwardly and heightwise of said support into engagement with a work piece thereon, and means for arresting 25 movement of said member forwardly of said support when said member is directly above said support.

46. In a machine for use in making shoes, a 30 work support, a pressing member, a lever on which said member is mounted, a link connected to said lever and mounted to swing toward and away from said support, and means for operating said lever to swing said link toward said support and then to move said pressing member 35 heightwise of said support into engagement with a work piece thereon.

47. In a machine for use in making shoes, a 40 work support, a pressing member, and operating means for said member comprising a lever, a toggle connected to said lever and a fulcrum for said lever, said fulcrum being movable toward and away from said support.

48. In a machine for use in making shoes, a 45 work support, a pressing member, means for operating said member comprising a lever and a toggle connected to said lever, means for yielding holding said toggle in collapsed condition, and a fulcrum for said lever mounted for limited movement toward said support, said toggle being 50 constructed and arranged to be straightened to swing said member about said fulcrum heightwise of said support after said fulcrum has reached the limit of its movement toward said support.

49. In a machine for use in making shoes, a 55 work support, a pressing member, a lever carrying said member, said lever being mounted for limited movement forwardly of said support and to swing heightwise thereof, a rotatably mounted 60 toggle, and means for holding said toggle in collapsed condition, said toggle being arranged to be rotated while in collapsed condition to move said lever forwardly of said support and then to be straightened whereby said lever is swung 65 heightwise of said support into engagement with a work piece thereon.

PAUL H. DIXON.
